(57) **CLAIM**

I claim the ornamental design for an truck wash paddle, as shown and described.

DESCRIPTION

FIG. 1 of the drawings is a perspective view showing the front side, the top, and a first side of a truck wash paddle embodying the design of my invention;

FIG. 2 is an elevation view of the a second side of the truck wash paddle;

FIG. 3 is a top view of the truck wash paddle;

FIG. 4 is an elevation view of the back side of the truck wash paddle;

FIG. 5 is a bottom view of the truck wash paddle; and,

FIG. 6 is a cross sectional view of the truck wash paddle as viewed in a bisecting plane that contains a line 6-6 in FIG. 5. The portions shown in broken lines in FIG. 1 are for illustrative purposes only and form no part of the claimed design; indicate a handle member; they indicate the position of a typical handle member mounted on the truck wash paddle. The truck wash paddle is a device for holding a car wash mitt on a handle member in order to facilitate washing of difficult-to-reach portions of a truck.
